UNITED STATES PATENT OFFICE.

GEORGE W. McCALL, OF PRICE, UTAH.

BED-SPRING TIGHTENER.

No. 841,804.

Specification of Letters Patent.

Patented Jan. 22, 1907.

Application filed June 30, 1906. Serial No. 324,246.

To all whom it may concern:

Be it known that I, GEORGE W. McCALL, a citizen of the United States, residing in Price, in the county of Carbon and State of Utah, have invented certain new and useful Improvements in Bed-Spring Tighteners, of which the following is a specification, reference being had to the accompanying drawings.

10 My invention relates to improvements in means for adjusting the degree of tightness of a bed-spring; and the object of my invention is to provide a device of this class which will be simple in construction, comparatively 15 cheap in manufacture, and efficient in operation.

In the drawings illustrating the principle of my invention and the best mode now known to me of applying that principle, Figure 1 is a 20 plan view, and Fig. 2 is a side view, of my improved bed-spring tightener.

The side rails *a* are connected at one end by a yoke *b*, in which is journaled the end of a shaft *c*, upon which is mounted a roller *d*, to 25 which is suitably secured one end of the bed-bottom or bed-spring *e*, the other end of which is fastened to a foot-piece. (Not shown.) One end *f* of the shaft *c* projects through the yoke *b* and is squared to engage a wrench *g*, by means of which the shaft *c* and its roller *d* 30 may be rotated. Secured to each end of the roller *d* is a ratchet-wheel *h*, the teeth of which are engaged by the toe of a pawl *i*, pivoted at *j* to one of the side rails and held in engagement with the teeth of the ratchet-wheel by means of a flat or leaf spring *k*.

The bed-bottom *e* is provided with loops *m*,

which engage the hooks *n*, formed on the top of the plate *o*. The side rails *a* are formed with slots *p*, through which pass bolts *q*, 40 which, in combination with the nuts *r*, secure the plates *o* to the side rails.

By rotating the shaft *c* by means of the wrench *g* the bed-spring may be tightened, and in order to prevent the bed-spring *e* 45 from contracting in width, and so to maintain the width of the bed-spring uniform throughout its length, the plates *o* are moved along the side rails in the slots *p* and have their hooked ends engaged with the loops formed 50 in the edges of the bed-bottom.

What I claim is—

The combination with a pair of slotted side rails, of a yoke which connects said side rails at one end thereof; a shaft journaled in said 55 yoke, one end of said shaft projecting from said yoke and having a squared end; a wrench which engages said squared end; a roller mounted fast upon said shaft; a pair of ratchet-wheels, one of which is secured to each 60 end of said roller; a pawl for each of said ratchet-wheels, said pawl being pivoted on the end of one of said side rails; a spring secured to one of said side rails and controlling said pawl; a bed-bottom formed with loops and 65 secured to said roller; a series of plates having hook ends which engage in said loops; and bolts which pass through the slots in said side rails for adjustably securing said plates to said side rails.

GEORGE W. McCALL.
